UNITED STATES PATENT OFFICE

102,418

DESIGN FOR A VEHICLE INDICATING DEVICE

Walter De Lisle, Windsor, Ontario, Canada

Application September 25, 1936, Serial No. 65,012
In Canada September 4, 1936

Term of patent 3½ years

To all whom it may concern:

Be it known that I, Walter De Lisle, a citizen of the Dominion of Canada, residing at 313 McKay, in Windsor, County of Essex, and Province of Ontario, have invented new, original, and ornamental Design for Vehicle Indicating Device, of which the following is a specification, reference being had to the accompanying drawing forming part thereof:

Fig. 1 is a front perspective view of a vehicle indicating device showing my new design; Fig. 2 is a top perspective view thereof; and Fig. 3 is a side elevational view thereof.

I claim:

The ornamental design for a vehicle indicating device, as shown.

WALTER DE LISLE.
